UNITED STATES PATENT OFFICE.

ANSIL MOFFATT, OF INDIANAPOLIS, INDIANA.

PENCIL-STERILIZING CASE.

SPECIFICATION forming part of Letters Patent No. 591,050, dated October 5, 1897.

Application filed December 26, 1896. Serial No. 617,010. (No model.)

To all whom it may concern:

Be it known that I, ANSIL MOFFATT, a citizen of the United States, residing at Indianapolis, in the county of Marion and State of Indiana, have invented certain new and useful Improvements in Pencil-Sterilizing Cases; and I do hereby declare the following to be a full, clear, and exact description of the invention, such as will enable others skilled in the art to which it appertains to make and use the same.

It becomes more apparent every year that contagious diseases like diphtheria are widely disseminated by the unsanitary practices of our common schools, where children are congregated in large bodies, and many of the diseases are transmitted by the careless interchange of penholders and pencils used in the school work. Because of the unconscious practice of placing the pencil or penholder in the mouth it is impossible to keep such articles free from whatever germs of disease the user may be afflicted with, and the usual careless exchange from one child to another of those articles makes the spread of a contagious disease an unavoidable consequence.

The object of this invention is, first, to provide a depository to receive and hold all of the penholders and pencils when they are not in use; second, to provide a marked place for each penholder or pencil, whereby each child will be able to know and reclaim its own property; third, to provide means for destroying the germs by subjecting the pencils to a degree of heat sufficiently high to accomplish that purpose or to expose them in this condition to antiseptic vapors.

Referring to the accompanying drawings, in which like letters of reference indicate like parts, Figure 1 is a view in perspective of one of the trays removed from the case and filled with pencils. Fig. 2 is a plan view of a tray with all of the pencils removed except one; Fig. 3, an end view of the case in which the trays are deposited, showing same filled with trays and showing the case broken away in places. Fig. 4 is a detail in longitudinal vertical section of the case filled with trays, and Fig. 5 is a view in perspective of a case made out of wire-cloth.

As the result of experience in the management of public schools it has been found that

fifty-six children to a room is the number calculated to give the best results, and the best modern construction of school-buildings conforms to those figures. The scholars are seated in seven tiers of eight pupils to each tier, and in carrying out my invention I propose to provide a separate tray for each tier of pupils and to provide holders for eight pencils or penholders in each of the trays.

A represents the trays, and B the case in which the trays are deposited.

The trays shown in Figs. 1 to 4, inclusive, are made out of sheet metal with parts bent up at right angles to form the ends A' and A². The end A' will have its top edge a' bent in at right angles to form a support for the superimposed trays when they are placed in the case and also to form a hold for the fingers in lifting the trays out of the case. The ends A² will be bent up at right angles to form the part a², parallel with the bottom, and then down diagonally to form the oblique section a³. The lower edge of the section a³ rests on the bottom of the tray, and the section is provided with eight perforations or holes a⁴ to receive the pencils, the ends of which are thrust into said holes in the manner shown in Fig. 1.

C is a spiral spring the ends of which are fastened to the bottom of the tray. The springs form holders for the pencils, which are placed between the coils of the springs in the manner clearly shown. In order to present the pencils longitudinally of the tray, the spring will be placed diagonally, as shown in Fig. 2.

D are the pencils (or they might be penholders) and each one is numbered from "1" to "8" consecutively. The holes in the diagonal section a³ are numbered from "1" to "8," whereby each student will have a certain place for his pencil and will be able to put it in its place without loss of time or danger of confusion. By inserting the end of the pencil in the hole where it belongs it will, thus guided, enter its proper place in the spring-holder C when the free end of the pencil is pressed down. The perforated section a³ marks the place for each pencil, affords a fulcrum for the ends of the pencils in pushing them into the spring-holder, and acts as a guide in directing them into place; but more important than all the

perforations admit the ends of the pencils into a box-like inclosure, which will protect them from contact with the fingers of other than the rightful owners in placing the pencils in place in the case and in removing them. This is especially important because the sharpened end of the pencil is the portion which the scholar habitually places in his mouth and is for that reason most liable to be 10 contaminated.

The sheet from which the tray is made will be bent up on one side to form the flange A⁵, the main purpose of which is to give stiffness to the tray. The opposite side of the tray is 15 left open to afford access to the pencils, which are purposely packed close together, so their removal from the tray must begin with the outside one, (No. 1,) and proceed in regular order through the lot. This avoids confusion 20 and makes more certain the delivery of each pencil to its rightful owner.

There are holes through the bottom of the trays. Each tray will preferably have two holes, which, when the trays are in the case, will 25 register with the corresponding holes in the trays above and below it. The case will have holes through its bottom in vertical alinement with the openings in the trays. These openings form hot-air flues and passage-ways for 30 antiseptic vapors when any are used.

The heat for destroying the germs may be applied by setting the filled case on top of a stove such as is commonly used in a school-room or by supporting the case over a lighted 35 lamp, and in order to keep the pencils from burning I provide an air-chamber F at the bottom of the case below the last tray. This is produced by placing an inverted tray G on the bottom of the case. This tray need only 40 consist of a top plate with the ends bent down to form supports. The plate will be perforated like the other trays.

The case will be provided with a lid H, which retains the heat and insures its thorough 45 efficient application to the work to be done.

In the modification shown in Fig. 5 the tray is made out of wire-cloth instead of sheet metal, and I have found by experience that sheet-wire causes less noise in handling the 50 trays than when made out of metal sheets. The meshes of the wire-cloth allow free circulation of heat and antiseptic vapors.

Having thus fully described my invention, what I claim as new, and wish to secure by 55 Letters Patent of the United States, is—

1. In a pencil-holder, a single sheet of metal perforated as described and forming the bottom and having one end bent up approximately at right angles and then forward parallel with the bottom, and having the other end bent up, and finally, down in an inclined position with the bottom, said inclined section having numbered openings to receive the ends of the pencils, and said sheet of metal 65 forming the bottom of the holder, having one side edge only, bent up to form a stiffening-flange and said bottom having holders to grasp the pencils.

2. The combination, with a case having a 70 perforated bottom and a close-fitting lid, of a plurality of trays containing pencils or pen-holders, said trays being made out of a single sheet of wire-cloth or perforated metal and having its ends bent up at right angles and 75 then inward approximately parallel with the bottom and having one of its ends bent downwardly and provided with numbered openings to receive the ends of the pencils and having one side edge only, bent up to form a 80 stiffening-flange, said bottom having holders to grasp the pencils, and said case to receive the trays having an air space or chamber between the lower tray and the bottom of the case, all substantially as described and for 85 the purposes specified.

In testimony whereof I affix my signature in presence of two witnesses.

ANSIL MOFFATT.
